UNITED STATES PATENT OFFICE.

SALVADOR CLAPERS, OF BALTIMORE, MARYLAND.

SLOT VENDING-MACHINE.

1,347,683.

Specification of Letters Patent. Patented July 27, 1920.

Application filed May 22, 1919. Serial No. 298,951.

To all whom it may concern:

Be it known that I, SALVADOR CLAPERS, a citizen of the United States, residing at Baltimore city, State of Maryland, have invented certain new and useful Improvements in Slot Vending-Machines, of which the following is a specification.

This invention relates to coin-controlled vending machines, and more particularly a machine which delivers an article the price of which is less than the coin which is required to operate the machine, and which automatically throws out with the article the correct change. Thus, if the price of 10 the article is, say, nine cents, and a ten-cent piece is required to operate the machine, then one cent will be thrown out with the article delivered. It will be understood of course, that the machine is not limited to 15 these particular coin values, and the parts may be arranged for various other coin values.

The invention has for its object to provide a novel and improved machine of the 20 kind stated, which is perfectly reliable in operation, and to this end, the invention consists in a combination and arrangement of parts to be hereinafter described and claimed.

30 In order that the invention may be better understood, reference is had to the accompanying drawings, forming a part of this specification.

In the drawings,

35 Figure 1 is a side elevation of the machine, partly in section;

Fig. 2 is a side elevation of certain parts of the mechanism viewed from the side opposite to that of Fig. 1;

40 Fig. 3 is a horizontal section on the line 3—3 of Fig. 2;

Fig. 4 is a cross section on the line 4—4 of Fig. 3;

Fig. 5 is an elevation showing a coin rest 45 or support, and

Fig. 6 is a view similar to Fig. 4 showing the parts in another position, with some of the parts appearing in Fig. 4 left off.

Referring specifically to the drawings, 10 50 denotes a cabinet in which the coin-controlled delivery mechanism is housed. The cabinet also contains a shelf 11 on which rests the supply of merchandise or articles 12 to be delivered, the same being arranged 55 in a stack or pile in an upright magazine 13 rising from the shelf. There is an open-

ing between the bottom of the magazine and the shelf to permit the articles to be ejected, this being done by a slidable pusher 14 working on top of the shelf and adapted 60 to be carried forwardly against the package or article at the bottom of the stack to slide the same rearwardly from beneath the latter, whereupon it drops on an incline 15 in the cabinet, beneath the shelf, and leading 65 to a delivery opening in the front wall of the cabinet, and slides down the incline to said opening.

The cabinet 10 also incloses an upright magazine 16 containing a supply 17 of coins 70 of a certain denomination. This magazine rises from a shelf 18, and at the rear of the shelf and the bottom of the magazine is a coin discharge opening 19 normally closed by a hinged gate 20. The coins are ejected 75 singly from the magazine by a slidable pusher 21 operating on the shelf 18 and adapted, when advanced, to push the coin at the bottom of the stack through the opening 19, the gate 20 being swung open by 80 the coin. The ejected coin drops on the incline 15 and slides down the same to the delivery opening in the front wall of the cabinet.

The two pushers 14 and 21 are operated 85 by a coin-controlled mechanism which will now be described:

On the shelf 11 are upstanding guide plates 22 between which the article pusher 14 slides, said plates having slots 22^a in 90 which work pins 23 extending from the sides of the pusher. Across the guide plates, above the pusher, extends a plate 24 which supports a frame carrying a spring motor, said frame being of suitable design 95 to support the motor and its associate parts. The frame includes three laterally spaced upright plates 25, 26 and 27, respectively.

Between the frame plates 25 and 26 is located a spiral spring 28 made fast at its 100 inner end to a shaft 29 journaled in said plates and in the plate 27, and anchored at its outer end to a cross pin 30 carried by the plates 25 and 26. On the shaft 29 is loosely mounted a spur gear 31 adapted to receive 105 motion from the shaft in one direction through a pawl-and-ratchet mechanism, a ratchet wheel 32 being fast on the shaft and having its teeth engageable by a pivoted, spring-pressed pawl 33 mounted on one side 110 of the gear.

The gear 31 is connected by a train of

gears to a shaft 34 journaled in the plates 26 and 27, and having a ratchet wheel 35 which is engageable by a pivoted detent 36, the latter extending from a rock shaft 37 5 journaled in the plates 26 and 27. From the rock shaft extends an actuating arm 38 the swing of which in a direction to disengage the detent being limited by a stop 39.

On the shaft 29, outside the plate 25, is 10 made fast an angle lever the two arms or branches of which are shown at 40 and 41, respectively. The lever arm 40 is adapted to bear against a bracket or abutment 42 fastened to one side of the slidable article 15 pusher 14 by one of the pins 23. This abutment extends outward far enough to come behind a post 43 rising from the top of the pusher 21, to actuate the latter, upon striking the post. The pusher 21 is retracted by 20 a spring 44 anchored at one end to the post 43 and at the other end to a post 45 rising from the shelf 18. A stop pin 46 rising from the shelf 18 limits the rearward or return movement of the pusher 21. A spring 25 47 is also connected to the pusher 14 for retracting the same, and this movement of the pusher is limited by the pins 23 and slots 22^a.

Above the mechanism hereinbefore described is a shelf 48 which extends from the 30 front wall of the cabinet 10 and supports a slide bar 49 for carrying into the machine the coin by which it is controlled, said bar having an aperture 50 of the same diameter, as the coin by which the machine is designed 35 to be controlled. When the slide bar is extended in its normal coin-receiving position, the aperture 50 is in line with an aperture 51 in the shelf 48 and of smaller diameter, so that a coin or a check smaller than the 40 proper coin will drop through and thus prevent the machine from being fraudulently operated. Complete withdrawal of the slide bar from the cabinet is prevented by a stop pin 52 on the former.

Inside the cabinet 10, the shelf 48 has a 45 coin aperture 53 through which the coin is adapted to drop, and beneath the shelf, in line with the aperture is a coin chute 54 leading to a receptacle 55. In the rear wall 54^a of this chute is an aperture 56 through which is adapted to be projected a pusher finger 57 pivotally carried by a shaft 58 supported by the plate 26 and the side walls of the cabinet. A spring 59 connected 50 to the finger 57 tends to swing the same in the direction of the aperture 56.

In the chute 54, in front of the aperture 56, is mounted a gate 60 the same being pivoted at the top, as shown at 61, to the side 60 walls of the chute. This gate normally extends with a downward inclination across the chute, its lower free edge resting on spaced flanges or ribs 62 on the rear wall 54^a, said ribs being located on opposite sides 65 of the aperture 56, and being spaced apart

at their upper ends a distance corresponding to the diameter of the coin to enable the latter to come therebetween. At the opening 56, the gate 60 has an aperture 63 which is in line with the finger 57.

The gate 60 has an arm 64 extending laterally from one of its side edges and the outer end of this arm has a bend 65 which is positioned to engage the arm 38 for tripping the detent 36. A spring 66 connected to the arm 64 tends to swing the gate in the direction of the chute wall 54^a.

On the end of the gate 60 opposite the end from which the arm 64 extends is an outstanding finger 67 which is in the path 80 of the lever arm 41, the outer end of the latter being cam-shaped, as shown at 68 so that when it engages the pin it forces the same in a direction to swing the gate away from the opening 56.

On the shaft 29 is also fixed an arm 69 carrying at its outer end a pivoted dog 70 which rests on top of the shelf 48 to the rear of the slide bar 49, and is adapted to be engaged by the latter to wind up the spring 90 28 as will be described hereinafter. From one side of the dog 70 extends a pin 71, which latter, when it slides over an inclined plate 72 carried by the shelf 48, lifts the dog 95 and trips it out of engagement with the rear edge of the slide bar 49 for a purpose to be presently described.

The operation of the machine may be summarized as follows:

In the normal position of the parts, the 100 slide bar 49 is projecting from the cabinet so that a coin may be placed in the aperture 50. The gate 60 is extending across the coin chute 54 with its free end resting on the ribs 62, and the finger 57 is extending 105 through the aperture 56 and also through the gate aperture 63 as shown in Fig. 4. Upon pushing the slide bar 49 inward, the coin in the aperture 50 is carried into the cabinet and when it comes over the aperture 110 53 it drops through the same into the chute and against the gate 60, and its progress down the chute, is stopped. The coin is now seating over the aperture 56 and between the ribs 62 which latter are spaced to admit the 115 coin therebetween. As shown in Fig. 5, the space between the ribs narrows downwardly to such an extent that the coin can not slide further when the finger 57 is retracted and it is then held between the ribs and by resting against the gate. On its inward movement, the rear end of the slide bar 49 pushes against the finger 57 and retracts it against the tension of the spring 59, leaving the coin over the opening and supported solely by the ribs 62 and the gate 60. This movement of the finger 57 is simultaneous with the drop of the coin to the gate 60. Shortly after the finger 57 swings back as described, the rear end of the slide engages 120 125 130

the dog 70 and through the arm 69 turns the shaft 29 in a direction to wind the spring 28. The slide bar 49 is now released, whereupon the finger 57 is swung forwardly by 5 the spring 59 through the opening 56, and upon striking the coin over the latter it presses the coin against the gate 60 causing the latter to swing back. This movement of the gate carries the bend 65 in a direction 10 to disengage the arm 38 and release the detent 36. The train of gears being now released, the shaft 29 is freed to be rotated by the spring 28, and the lever arm 40 swings in a direction to engage the abutment 42 and 15 advance the pushers 14 and 21 to eject the lowermost article from the stack 12 and a coin from the magazine 16. More than one coin may be ejected by increasing the thickness of the pusher 21 to correspond to the 20 combined thickness of the number of coins to be ejected simultaneously. When the shaft 29 is turning to effect the ejecting operation, the arm 69 swings forward, and the dog 70 is tripped off the rear edge of the 25 slide bar 49 by the pin 71 riding up the incline 72. This is for the purpose of preventing the slide bar from being thrown forwardly with such force as to injure the operator. When the lever arm 40 swings 30 to operate the article pushers, the lever arm 41 swings forwardly and its cam edge 64 engages the finger 67 to hold the gate 60 open, and when the slide bar 49 is again pushed in for another operation, the lever 35 arm leaves the finger and allows the gate to be pulled back to the position shown in Figs. 4 and 5 by the spring 66.

The spring 28 is rewound after each delivery stroke, and hence after being initially wound, it remains under sufficient tension to operate the article pushers. After 40 the gate 60 is forced back by the advancing finger 57 pushing the coin thereagainst, the latter is pushed into the chute and drops 45 down the same into the box 55.

The pushers 14 and 21 are normally advanced, and they are retracted into position for ejecting the article and the coin, by the springs 47 and 44 when the slide bar 49 is 50 pushed inwardly, the lever arm 40 then swinging back through the movement imparted by the dog 70 and arm 69 to the shaft 29 in a direction to wind the spring 28 as hereinbefore described.

In order that the number of coins to be 55 ejected from the magazine 16 may be varied, the side walls of the latter are carried a short distance below the shelf, and have their inner faces provided with guide grooves 60 16^a in which is adapted to be supported a plate 20^a having slots 20^b. This plate forms a bottom for the magazine and the stack of coins rests thereon. When the plate is positioned as shown in Fig. 1, its top is flush 65 with the bottom of the pusher 21, and hence

if the thickness of the latter corresponds to the combined thickness of two coins, a corresponding number of coins will be ejected when the pusher is actuated. If more than two coins are to be ejected, the plate 20^a 70 will be placed farther down to lower the stack of coins, so that when the pusher is actuated it ejects the two coins with which it comes directly into contact, and also the coin or coins below the same. The pusher 75 75 has depending pins 21^a to engage the aforementioned coin or coins below the same, and these pins work in the slots 20^b of the plate 20^a. The gate 20 is behind the plate 20^a, and swings open as hereinbefore described to 80 allow the coins to pass.

I claim:

1. In a coin-controlled vending machine, an article ejector, ejector operating means, a detent for locking the ejector operating 85 means, a coin-chute, means for delivering a coin into the chute, a pivoted member in the chute and having an opening, means carried by said member for operating the detent to release the ejector operating means, means in the chute for supporting a coin over the opening in the pivoted member, and means controlled by the aforesaid coin-delivery means for pushing the coin against the pivoted member for swinging the same to operate the detent. 90

2. In a coin-controlled vending machine, an article ejector, ejector operating means, a detent for locking the ejector operating means, a coin-chute having an opening in 100 its wall, means for delivering a coin into the chute, a pivoted member in the chute opposite the opening in the wall thereof, said member also having an opening and normally extending across the chute to act as a 105 barrier for the coin, means carried by said member for operating the detent, and means controlled by the aforesaid coin-delivery means for pushing the coin against the pivoted member for swinging the same to operate the detent. 110

3. In a coin-controlled vending machine, an article ejector, a spring motor, a shaft operated by said motor, lever arms extending from the shaft, one of said arms operating 115 the ejector and the other arm being adapted to turn the motor shaft in a direction to wind the motor spring, a detent for locking the motor, coin-controlled means for operating the detent to release the motor, and a slide bar for delivering a coin into the machine, said bar actuating the aforesaid spring-winding arm. 120

4. In a coin-controlled vending machine, an article ejector, a spring motor, a shaft 125 operated by said motor, lever arms extending from the shaft, one of said arms operating the ejector and the other arm being adapted to turn the motor shaft in a direction to wind the motor spring, a detent for 130

- locking the motor, coin-controlled means for operating the detent to release the motor, a slide bar for delivering a coin into the machine, and a pivoted dog carried by the aforesaid spring-winding arm, and engageable by the slide bar for actuating said arm to wind the spring.
- 5 5. In a coin-controlled vending machine, an article-ejector, a spring-motor, a shaft operated by said motor, lever arms extending from the shaft, one of said arms operating the ejector and the other arm being adapted to turn the motor-shaft in a direction to wind the motor spring, a detent for locking the motor, coin-controlled means for operating the detent to release the motor, a slide bar for delivering a coin into the machine, a pivoted dog carried by the aforesaid spring-winding arm, and engageable by the slide bar for actuating said arm to wind the spring, and means for tripping the dog away from the slide bar on the return stroke thereof.
- 10 6. In a coin-controlled vending machine, an article-ejector, ejector-operating means, a detent for locking the ejector-operating means, a coin-chute, a pivoted member in the chute and having an opening, means car-

ried by said member for operating the detent to release the ejector-operating means, 30 means in the chute for supporting a coin over the opening in the pivoted member, a slide for delivering a coin into the chute, and means controlled by the slide for pushing a coin against the pivoted member for 35 swinging the same to operate the detent.

7. In a coin-controlled vending machine, an article-ejector, ejector-operating means, a detent for locking the ejector-operating means, a coin-chute, a pivoted member in the 40 chute and having an opening, means carried by said member for operating the detent to release the ejector-operating means, means in the chute for supporting a coin over the opening in the pivoted member, a 45 slide for delivering a coin into the chute, and a pivoted spring-actuated finger controlled by the slide for pushing a coin against the pivoted member for swinging the same to operate the detent.

50 In testimony whereof I affix my signature in the presence of two witnesses.

SALVADOR CLAPERS.
